CHLORINATION OF ALIPHATIC HYDROCARBONS

Edgar C. Britton, Gerald H. Coleman, and Bartholdt C. Hadler, Midland, Mich., assignors to The Dow Chemical Company, Midland, Mich., a corporation of Michigan

No Drawing. Application February 1, 1933,
Serial No. 654,770

16 Claims. (Cl. 260—166)

The present invention concerns an improved method of producing chlorinated aliphatic hydrocarbons through the direct chlorination of an aliphatic hydrocarbon containing from three to five carbon atoms, inclusive. The invention more particularly concerns a treatment of a chlorinated aliphatic hydrocarbon mixture to convert undesirable olefinic by-products into saturated chloro-hydrocarbons, whereby the yield of desirable products is increased and the procedure involved in isolating such desirable products from the chlorination mixture is rendered relatively simple and inexpensive.

In our co-pending application, Serial No. 636,996, filed October 10, 1932, we have disclosed that, when an aliphatic hydrocarbon containing from three to five carbon atoms is chlorinated in vapor phase according to usual methods, a complex and difficultly separable mixture containing unreacted hydrocarbon, monochlorinated hydrocarbons, polychlorinated hydrocarbons, olefines, chloro-olefines, and hydrogen chloride is obtained.

The presence of olefines and chloro-olefines in the chlorinated mixture is highly disadvantageous. After an aliphatic hydrocarbon has been chlorinated it is usual practice to scrub the reacted mixture with water to remove hydrogen chloride therefrom, then to condense the chlorinated hydrocarbon products from the residual mixture. The condensate is fractionally distilled to separate the chlorinated hydrocarbon products. Vapors, which remain after condensing the chlorinated hydrocarbon products from the chlorination mixture, usually consist substantially of the unreacted aliphatic hydrocarbon along with one or more olefines derived therefrom. Such remaining vapors are returned to the chlorination wherein the unreacted hydrocarbon is chlorinated to form an additional quantity of chlorinated hydrocarbon products. During chlorination of such residual vapors, however, the olefines present are chlorinated to form polychlorinated products and frequently are polymerized to form tars.

The condensate, which is obtained when the chlorinated hydrocarbon products are condensed from a chlorination mixture in accordance with the above described usual procedure, consists substantially of a solution of saturated chlorinated hydrocarbons, i. e. alkyl chlorides and polychlorinated products, having the chloro-olefine by-products dissolved therewith. Such chloro-olefines usually boil at substantially the same temperature as does an alkyl chloride product,

hence the latter can not readily be separated in a form free from contamination with chloro-olefines and the so-contaminated alkyl chloride can not be purified completely through fractional distillation thereof. For instance, during the vapor phase chlorination of isobutane, chloro-isobutylenes are usually formed which boil at substantially the same temperature as does isobutyl chloride (one of the principal products from the chlorination) which latter we have been unable satisfactorily to separate from such chloro-isobutylene through fractional distillation. Again, during chlorination of propane, chloro-propylenes, e. g. allyl chloride, are often formed. Allyl chloride (B. P. approximately 45° C.) can not readily be fractionally distilled from normal propyl chloride (B. P. 46.5° C.) which is one of the products from the chlorination. The presence of an appreciable quantity of a chloro-olefine in an alkyl chloride seriously reduces the value of the latter as a commercial product and such chloro-olefine impurity frequently interferes with reactions in which it is desired to employ the alkyl chloride as a reactant.

We have now found that, when an aliphatic hydrocarbon containing from three to five carbon atoms is reacted with chlorine to obtain a mixture consisting substantially of chlorinated hydrocarbon products, hydrogen chloride, olefines, and chloro-olefines along with any aliphatic hydrocarbon which may remain unreacted, such chlorination mixture may be treated to effect a chemical combination of the hydrogen chloride with the olefinic by-products, e. g. olefines and chloro-olefines, whereby the latter are converted into saturated chlorinated hydrocarbons. The separation of chlorinated products from the mixture may then be carried out with relative ease. Any unreacted aliphatic hydrocarbon present may readily be separated in a form substantially free of olefines, and such unreacted hydrocarbon may be returned to the chlorination without danger of appreciably increasing the quantity of polychlorinated products and/or tars formed during such chlorination.

To the accomplishment of the foregoing and related ends, the invention consists in the method hereinafter fully described and particularly pointed out in the claims, the following description and example setting forth in detail but several of the various ways in which the principle of our invention may be employed.

The chlorination of an aliphatic hydrocarbon containing from three to five carbon atoms may be carried out at a temperature above 160° C.,

- preferably above 200° C., in any of the usual ways. In practice, we prefer to pass chlorine and the vaporized aliphatic hydrocarbon reactant into a mixing chamber at such respective rates that a mixture of chlorine with at least its molecular equivalent of the aliphatic hydrocarbon is formed. The aliphatic hydrocarbon may be employed in as great an excess as desired, but we usually find it most economical to mix chlorine with between 1 and 10 times its molecular equivalent of the hydrocarbon reactant. The above reactants are preferably mixed in the dark at a temperature below about 125° C.
- The mixture of chlorine and the hydrocarbon reactant is then passed in continuous flow through a reaction chamber heated to a temperature usually above 200° C., wherein a reaction takes place with formation of a mixture containing hydrogen chloride, saturated chloro-hydrocarbons, an olefine, and chloro-olefines. When the chlorination is carried out at a temperature below about 300° C., the reacting mixture may advantageously be exposed to actinic light so as to assure rapid and complete reaction.
- At temperatures above about 300° C., the chlorination usually proceeds smoothly and with sufficient rapidity in the absence of light, although light may be used to catalyze the reaction at such higher temperatures, if desired.
- The chlorination should be carried out at a temperature below that at which organic components of the reaction mixture are appreciably carbonized. The exact temperature above which carbonization will take place to an objectionable extent is dependent upon the particular aliphatic hydrocarbon to be chlorinated, the ratio of chlorine to such hydrocarbon reactant, the period of time over which a given quantity of reaction mixture is maintained under the reaction conditions, the composition of surfaces in contact with the reacting mixture, etc. The upper temperature at which a chlorination may successfully be carried out is dependent, then, upon the exact operating conditions to be employed and can not be specified. However, we usually carry such chlorination out at a temperature below about 600° C. In general, if considerable carbonization is observed during a chlorination, the reaction temperature may be lowered to correct the difficulty.
- The chlorinated mixture is cooled to a temperature below about 200° C., preferably below 100° C., and the cooled mixture is subjected to conditions which cause reaction to take place between the hydrogen chloride and olefinic by-products from the chlorination, whereby said olefinic by-products are converted into desirable saturated compounds, e. g. alkyl chlorides, dichloro-hydrocarbons, etc., and the yield of said saturated compounds is increased. Such reaction may be brought about by contacting the cooled chlorination mixture with a catalyst capable of promoting chemical combination of hydrogen chloride with olefines, or by subjecting the mixture to superatmospheric pressure, or both. Any of a wide variety of catalysts may be used for such purpose, among which are alkaline earth metal chlorides, antimony trichloride, bismuth trichloride, ferric chloride, aluminum oxide, kaolin, silica gel, etc. For convenience, such catalysts are hereinafter referred to as "hydrohalogenation catalysts". With a catalyst, the reaction may be carried out at atmospheric or even at subatmospheric pressure. In the absence of a catalyst, the reaction may be brought about by subjecting the mixture to superatmos-

pheric pressure, e. g. 150 pounds per square inch. However, regardless of whether or not a catalyst is used to promote such reaction, we prefer to carry the reaction out at a pressure considerably higher than atmospheric, e. g. 150 pounds per square inch, since an increase in pressure tends to promote the chemical combination of hydrogen chloride with olefines. 5

After the olefinic components of the chlorination mixture have been converted into saturated compounds through procedure similar to that described above, said mixture may be separated into its components in any of the usual ways. For instance, the chlorinated hydrocarbon products may be condensed to leave a vapor mixture 15 consisting substantially of hydrogen chloride and unreacted aliphatic hydrocarbon. Hydrogen chloride may be removed from such vapor mixture by scrubbing the latter with water and the residual unreacted hydrocarbon vapors may be 20 returned to the chlorination. The mixture of chlorinated hydrocarbons which had been condensed may be fractionally distilled to isolate the alkyl chloride and polychlorinated hydrocarbon products. 25

As procedure alternative to that described above, a chlorination mixture, which has been treated in the manner described so as to convert olefinic components thereof into saturated compounds, may be cooled (preferably under super- 30 atmospheric pressure) sufficiently to condense substantially all organic components thereof, the residual hydrogen chloride vapors may be separated directly from the condensate, and the latter may be fractionally distilled to isolate the various reaction products. The unreacted hydrocarbon fraction which is collected during such distillation may, of course, be returned to the chlorination.

The following table sets forth data collected 40 during two comparative chlorinations of isobutane. Run 1 was carried out according to usual procedure without any attempt being made to convert the undesirable olefinic by-products, e. g. isobutylene and chloro-isobutylenes, into saturated compounds and serves merely as a basis for comparison with run 2; which was carried out under similar conditions, except that a step was introduced whereby olefinic by-products were converted into useful saturated compounds in 50 accordance with our invention. In run 1 a mixture of chlorine with 1.12 times its molecular equivalent of 95 per cent pure isobutane was passed in continuous flow through a heated reaction chamber wherein the chlorine was completely reacted in the absence of light. The vapors issuing from the reaction chamber were cooled sufficiently to condense the major portion of the polychlorinated products and still leave the major portion of the monochlorinated products in vapor state. The remaining vapors were scrubbed with water to remove hydrogen chloride therefrom. During the scrubbing operation, a relatively small quantity (about 50 grams) of organic material was condensed, which was separated from the wash water, combined with the condensate collected prior to the scrubbing operation, and the combined condensate (I) was analyzed. The analysis of said combined condensate is to be found in the following table 70 under the heading "Condensate I". The vapors remaining after the scrubbing operation were cooled to about -70° C. so as to condense substantially all organic components thereof. The analysis of the condensate collected after the 75

scrubbing operation is to be found in the table under the heading "Condensate II".

Run 2 of the following table was made under operating conditions similar to those employed in run 1, except that immediately following the step of condensing polychlorinated products from the crude chlorination mixture, the residual vapors were passed, at atmospheric pressure, through a 1 inch tube containing granular kaolin for 44 inches of its length. During passage of vapors through said tube the latter was maintained at a temperature between 70° and 80° C. The vapors were then scrubbed with water to remove hydrogen chloride therefrom, the residual vapors were condensed, and the condensate (II) was analyzed. A small quantity of organic material which was condensed during the scrubbing operation was separated from the wash water, combined with the condensate collected prior to said scrubbing operation, and the combined condensate (I) was analyzed.

Table

Run No.	1	2
Isobutane (95% pure) moles/hour	4.18	4.18
Chlorine (98-99% pure) moles/hour	3.71	3.71
Molecular ratio isobutane/chlorine	1.12	1.12
<i>Operating conditions</i>		
Duration of run—hours	7.5	4.0
Chlorination temperature—° C.	330	330
Temperature at which polychlorinated products were condensed—° C.	24	24
Temperature of kaolin catalyst—° C.	70-80	
<i>Condensate I</i>		
Weight—grams	466	452
Analysis—per cent by weight:		
Isobutane	3.7	7.8
Polychlorinated products	78.0	70.0
Isobutyl chloride	11.5	14.7
Tertiary-butyl chloride	1.9	4.0
Chloro-isobutylenes	4.9	3.5
<i>Condensate II</i>		
Weight—grams	2,451	1,000
Analysis—per cent by weight:		
Isobutane	42.8	46.2
Polychlorinated products	3.3	5.0
Isobutyl chloride	36.7	36.2
Tertiary-butyl chloride	7.6	11.74
Chloro-isobutylene	7.3	0.26
Isobutylene	2.3	0.6

In the foregoing table, the comparative condensates (II) illustrate certain advantages of our invention. Condensate II of run 2 represents a fraction of a chlorination mixture which had been treated, in accordance with our invention, to convert olefinic by-products of the chlorination into the desired saturated compounds. Condensate (II) of run 1 is an analogous fraction from a similar chlorination, except that said condensate from run 1 did not receive treatment to convert the olefinic by-products into saturated compounds. A comparison of the condensates (II) shows that by a simple application of the principle of our invention the percentage, by weight, of tertiary-butyl chloride in such condensate was increased from 7.6 to 11.74; the percentage of chloro-isobutylenes was decreased from 7.3 to 0.26; and the percentage of isobutylene in such condensate was decreased from 2.3 to 0.6. Stated in terms of the percentage change of actual quantities of said compounds in condensates (II), the application of our invention resulted in a 54.5 per cent increase in the weight of tertiary-butyl chloride obtained in a given quantity of such

condensate; a 96.4 per cent decrease in the weight of chloro-isobutylenes; and a 74 per cent decrease in the weight of isobutylene obtained in a given quantity of such condensate.

The principle of our invention may be employed in ways other than those hereinbefore stated. For instance, the entire mixture obtained by chlorinating an aliphatic hydrocarbon may be treated according to our method to convert the olefines and chloro-olefines present into desirable saturated compounds and the so-treated mixture may be separated into its components in any of the usual ways.

Our improved method of making chlorinated aliphatic hydrocarbons is applicable to the chlorination of any aliphatic hydrocarbon containing from three to five carbon atoms, e. g. propane, normal butane, normal pentane, isopentane, etc. During a vapor phase chlorination of any of said hydrocarbons, according to usual methods, olefinic by-products are formed which may readily be converted into valuable saturated compounds by our present method.

Our invention, in brief, comprises chlorinating an aliphatic hydrocarbon, containing from three to five carbon atoms, in vapor phase at a temperature above 160° C. and then treating the reaction mixture to convert olefinic by-products contained therein into valuable saturated compounds.

In the following claims, the expression "chloro-isobutanes" shall be understood to refer to saturated chlorine derivatives of isobutane, e. g. isobutyl chloride, tertiary-butyl chloride, 1,3-dichloro-isobutane, etc., and the expression "mono-chloro-isobutanes" shall be understood to refer to isobutyl chloride and tertiary-butyl chloride.

Other modes of applying the principle of our invention may be employed instead of those explained, change being made as regards the method herein disclosed, provided the step or steps stated by any of the following claims or the equivalent of such stated step or steps be employed.

We therefore particularly point out and distinctly claim as our invention:

1. In a method of chlorinating saturated aliphatic hydrocarbons wherein chlorine is reacted with a saturated aliphatic hydrocarbon, containing from three to five carbon atoms, to form a mixture containing saturated chloro-hydrocarbons, hydrogen chloride, and olefinic compounds, the step which consists in reacting hydrogen chloride, formed during the chlorination, with said olefinic compounds at a temperature below about 200° C. to convert the latter into saturated chloro-hydrocarbons.

2. In a method of chlorinating saturated aliphatic hydrocarbons, the steps which consist in reacting chlorine with a saturated aliphatic hydrocarbon, containing from three to five carbon atoms, to form a mixture containing saturated chloro-hydrocarbons, hydrogen chloride, and olefinic compounds, and then reacting the hydrogen chloride with the olefinic compounds in such mixture while maintaining the latter at a temperature below about 200° C.

3. In a method of chlorinating saturated aliphatic hydrocarbons, the steps which consist in reacting chlorine with a saturated aliphatic hydrocarbon, containing from three to five carbon atoms, in vapor phase at a temperature above about 160° C., to form a mixture containing saturated chloro-hydrocarbons, hydrogen chloride, and olefinic compounds, and then reacting the hydrogen chloride with the olefinic components of

- such mixture while maintaining the latter at a temperature below about 200° C.
4. In a method of chlorinating saturated aliphatic hydrocarbons, the steps which consist in reacting chlorine with a saturated aliphatic hydrocarbon, containing from three to five carbon atoms, in vapor phase at a temperature above about 200° C., to form a mixture containing hydrogen chloride and olefinic compounds and then
- 10 contacting the chlorination mixture, at a temperature below about 200° C., with a hydrohalogenation catalyst to effect chemical combination between said hydrogen chloride and olefinic compounds.
- 15 5. In a method of chlorinating saturated aliphatic hydrocarbons, the steps which consist in reacting chlorine with a saturated aliphatic hydrocarbon, containing from three to five carbon atoms, in vapor phase at a temperature above
- 20 about 200° C., to form a mixture containing monochlorinated hydrocarbons, polychlorinated hydrocarbons, hydrogen chloride and olefinic compounds, cooling the reacted mixture sufficiently to condense polychlorinated hydrocarbon
- 25 products therefrom, and contacting the residual vapors, at a temperature below about 100° C., with a hydrohalogenation catalyst to effect chemical combination between said hydrogen chloride and olefinic compounds.
- 30 6. In a method of chlorinating saturated aliphatic hydrocarbons, the steps which consist in reacting a mixture of chlorine with at least its molecular equivalent of a saturated aliphatic hydrocarbon containing from three to five carbon atoms, in vapor phase at a temperature above
- 35 about 200° C., to form a mixture containing unreacted hydrocarbon, monochlorinated hydrocarbons, polychlorinated hydrocarbons, hydrogen chloride and olefinic compounds, cooling the re-
- 40 acted mixture sufficiently to condense polychlorinated hydrocarbons therefrom and still leave the major portion of the monochlorinated hydrocarbon products in vapor state, contacting the vapors, at a temperature below about 100° C.,
- 45 with a hydrohalogenation catalyst to effect chemical combination between said hydrogen chloride and olefinic compounds, thereafter scrubbing the vapor mixture with water to remove hydrogen chloride therefrom, condensing and separating
- 50 chlorinated hydrocarbon products from the residual vapors to leave vapors consisting substantially of the unreacted aliphatic hydrocarbon, and returning the latter to the chlorination.
- 55 7. In a method of chlorinating saturated aliphatic hydrocarbons, the steps which consist in reacting chlorine with a saturated aliphatic hydrocarbon, containing from three to five carbon atoms, in vapor phase at a temperature above
- 60 about 160° C., to form a mixture containing saturated chloro-hydrocarbons, hydrogen chloride, and olefinic compounds, and thereafter subjecting the chlorination mixture to a sufficiently high pressure to cause reaction between the hydrogen chloride and olefinic components of the mixture with resultant formation of an additional quantity of saturated chloro-hydrocarbons.
- 65 8. In a method of chlorinating saturated aliphatic hydrocarbons, the steps which consist in reacting a mixture of chlorine with at least its molecular equivalent of a saturated aliphatic hydrocarbon, containing from three to five carbon atoms, in vapor phase at a temperature above
- 70 about 200° C., cooling the reacted mixture sufficiently to condense polychlorinated hydrocarbons

therefrom and still leave the major portion of the monochlorinated hydrocarbon products in vapor state, and subjecting the residual vapor mixture, at a temperature below about 200° C., to a sufficiently high pressure to cause reaction 5 between the hydrogen chloride and olefinic components of the mixture with resultant formation of an additional quantity of saturated chloro-hydrocarbons.

9. In a method wherein chlorine is reacted with 10 isobutane to form a mixture containing chloro-isobutanes, hydrogen chloride, isobutylene, and chloro-isobutylene, the step which consists in reacting the hydrogen chloride with the isobutylene and chloro-isobutylene to form an addition- 15 al quantity of chloro-isobutanes.

10. The method which comprises chlorinating isobutane to form a mixture containing chloro-isobutanes, hydrogen chloride, isobutylene, and chloro-isobutylene, and then reacting the hydro- 20 gen chloride with the isobutylene and chloro-isobutylene to form an additional quantity of chloro-isobutanes.

11. The method which comprises reacting chlorine with isobutane, in vapor phase at a tem- 25 perature above about 160° C., to form a mixture containing chloro-isobutanes, hydrogen chloride, isobutylene, and chloro-isobutylene, and then re- acting the hydrogen chloride with the isobutylene and chloro-isobutylene at a temperature below 30 about 200° C. to form an additional quantity of chloro-isobutanes.

12. The method which comprises reacting chlorine with isobutane in vapor phase at a temper- 35 ature above about 200° C., to form a mixture con- taining hydrogen chloride and olefinic com- pounds, and then contacting the chlorination mixture, at a temperature below about 200° C., with a hydrohalogenation catalyst to effect chem- 40 ical combination between said hydrogen chloride and olefinic compounds.

13. The method which comprises reacting chlorine with isobutane in vapor phase at a temper- 45 ature above about 200° C., to form a mixture con- taining monochloro-isobutanes, polychloro-isobu- 50 tanes, hydrogen chloride and olefinic compounds, cooling the reacted mixture sufficiently to con- dense polychloro-isobutanes therefrom and still leave the major portion of the monochloro-isobutane products in vapor state, and contacting the residual vapor mixture, at a temperature be- 55 low about 100° C., with a hydrohalogenation cata- 60 yst to effect chemical combination between said hydrogen chloride and olefinic compounds.

14. The method which comprises reacting a 55 mixture of chlorine with at least its molecular equivalent of isobutane in vapor phase at a tem- 65 perature above about 200° C., to form a mixture containing unreacted isobutane, monochloro-isobutanes, polychloro-isobutanes, hydrogen chloride and olefinic compounds, cooling the reacted mix- 70 ture sufficiently to condense polychloro-isobutanes therefrom and still leave the major portion of the monochloro-isobutane products in vapor state, contacting the vapors, at a temperature be- 75 low about 100° C., with a hydrohalogenation cata- 80 yst to effect chemical combination between said hydrogen chloride and olefinic compounds, there- 85 after scrubbing the vapor mixture with water to remove hydrogen chloride therefrom, condens- 90 ing and separating chloro-isobutane products from the residual vapors to leave vapors con- 95 sisting substantially of unreacted isobutane, and returning the latter to the chlorination.

15. The method which comprises reacting chlo- 75

rine with isobutane, in vapor phase at a temperature above about 160° C., to form a mixture containing chloro-isobutanes, hydrogen chloride, isobutylene, and chloro-isobutylene, and thereafter subjecting the chlorination mixture to a sufficiently high pressure to cause the hydrogen chloride to react with isobutylene and chloro-isobutylene to form an additional quantity of chloro-isobutanes.

10 16. The method which comprises reacting a mixture of chlorine with at least its molecular equivalent of isobutane, in vapor phase at a temperature above about 200° C., cooling the reacted

mixture sufficiently to condense polychloro-isobutanes therefrom and still leave the major portion of the monochloro-isobutane products in vapor state and subjecting the residual vapor mixture, at a temperature below about 200° C., 5 to a sufficiently high pressure to cause the hydrogen chloride to react with the isobutylene and chloro-isobutylene components of the mixture with resultant formation of an additional quantity of chloro-isobutanes.
